US0D1048410S

(12) **United States Design Patent** (10) **Patent No.:** **US D1,048,410 S**
(45) **Date of Patent:** **** Oct. 22, 2024**

(54) **FINGERTIP PULSE OXIMETER**

(71) Applicant: **SHENZHEN IMDK MEDICAL TECHNOLOGY CO., LTD**, Shenzhen (CN)

(72) Inventor: **Changchun Xia**, Wenzhou (CN)

(73) Assignee: **SHENZHEN IMDK MEDICAL TECHNOLOGY CO., LTD**, Shenzhen (CN)

(**) Term: **15 Years**

(21) Appl. No.: **29/835,280**

(22) Filed: **Apr. 18, 2022**

(51) LOC (14) Cl. **24-02**

(52) U.S. Cl. USPC **D24/169**

(57) **CLAIM**

The ornamental design for a fingertip pulse oximeter as shown and described.

DESCRIPTION

FIG. 1 is a top, front, right side perspective view of a fingertip pulse oximeter, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the drawing depict portions of the fingertip pulse oximeter that form no part of the claimed design.

1 Claim, 7 Drawing Sheets
